DESIGN FOR A DISPLAY ARTICLE OR THE LIKE

John J. Reinhold and Albert C. Reinhold,
Marietta, Pa.

Application May 1, 1943, Serial No. 110,098

Term of patent 7 years

To all whom it may concern:

Be it known that we, John J. Reinhold and Albert C. Reinhold, citizens of the United States, residing in Marietta, county of Lancaster, State of Pennsylvania, have invented a new, original, and ornamental Design for a Display Article or the like, of which the following is a specification, reference being had to the accompanying drawing, forming part thereof.

Fig. 1 is a front elevational view of a display article showing our new design; and Fig. 2 is a side view of the same.

We claim:

The ornamental design for a display article or the like, as shown.

JOHN J. REINHOLD.
ALBERT C. REINHOLD.
